(57) **CLAIM**

The ornamental design for a power male connector, as shown and described.

DESCRIPTION

FIG. 1 is a front, bottom, and left side perspective view of a power male connector showing my new design;

FIG. 2 is a front plane view thereof;

FIG. 3 is a back plane view thereof;

FIG. 4 is a left side view thereof;

FIG. 5 is a right side view thereof;

FIG. 6 is a top plan view thereof; and,

FIG. 7 is a bottom plan view thereof.

The broken line in FIG. 3 represents unclaimed environment only and forms no part of the claimed design.
